UNITED STATES PATENT OFFICE.

ROBERT W. SCOTT, OF BABYLON, NEW YORK.

DEVICE FOR MACHINE-KNITTING WITH AUXILIARY YARNS.

1,370,490.

Specification of Letters Patent.

Patented Mar. 1, 1921.

Application filed May 20, 1920. Serial No. 382,961.

To all whom it may concern:

Be it known that I, ROBERT W. SCOTT, a citizen of the United States of America, and resident of Babylon, in the county of Suffolk 5 and State of New York, have invented new and useful Improvements in Devices for Machine-Knitting with Auxiliary Yarns, of which the following is a specification.

This invention relates to devices for making thickened wale structures, such as mock seams, in knit articles, such as hosiery or welted hosiery.

I have heretofore shown and described in my United States Patent No. 1,256,834, dated 15 Feb. 19, 1918, an article of hosiery having a thickened-wale or mock-seam and a method of making the same. A preferred instrument for the manufacture of such fabrics is more fully shown, described and claimed in my 20 application for United States Patent Ser. No. 114,096, filed August 10, 1916. As explained in my said Patent No. 1,256,834, a desirable machine for the manufacture may conform in the main to the machine shown, 25 described and claimed in my Letters Patent No. 1,282,958, dated Oct. 29, 1918, in connection with which the main and splicing yarn feeding means illustrated in my Patent No. 1,256,062, Feb. 12, 1918 may be employed 30 with advantage.

In any use of mechanism for the manufacture of inturned welts on tubular knit articles the operation involves the taking and holding of bights or loops near the beginning edge of the welt during the knitting 35 fabric for the welt, and the subsequent transfer to the needles for knitting the body of the article of the taken or held loops.

When it is sought to make the thickened-wale or mock-seam of my Patent No. 1,256,834, above, on a machine having any type of device for providing an automatically-made uniting course for an inturned welt, the operation of the mock-seam or thickened-wale device may be seriously interfered with by the welt holding and retransferring means, or by the yarn feeding devices, or by other causes. For instance, in the operation of my machine of Patent No. 50 1,282,958 above, it sometimes happens that by reason of a mispositioned knitting needle, a bent or deformed transfer bit or other causes, a bight intended for the uniting

course and taken by the transfer bits at the proper time is not transferred to the needles 55 at the later time intended, but remains engaged with the transfer bit; or it happens that through breakage or exchange of yarn an end of yarn from somewhere within the welt fabric or from a previous article may 60 extend up past the edge of the transfer dial carrying the bits. There will result a run or runs of yarn crossing the normal free space between the knitting needles relied upon to knit the body of the fabric and the transfer 65 dial. The presence of such a yarn is not detrimental to the manufacture of the stocking proper, since the strain of the growing fabric will either rupture the yarn or release it or pull out the end of the yarn, and no 70 harm is done. But when the manufacture includes a mock-seam or thickened-wale made according to the method of my Patent No. 1,256,834, the presence of such a yarn or other obstruction within and above the operating set of knitting needles may result in 75 detaining long bights of the thickened auxiliary yarn within the needle cylinder, and preventing proper formation of the thickened wale.

A principal object of the present invention is to enable the manufacture of thickened wale stockings or other articles on machines having auxiliary appliances, such as in-turned welting mechanism, in such a manner 85 as to insure the proper operation of the thickening wale mechanism.

In the accompanying drawings,—

Figure 1 is a left side elevation partly in vertical axial cross-section through a knitting machine equipped for making inturned welts and for making thickened wales or mock seams, and having the present invention applied thereto;

Fig. 2 is a detail of the matters shown in Fig. 1 illustrating the operation of an instrument employed to press the welt fabric beneath the dial;

Fig. 3 is a similar detail illustrating the position and operation of the same instrument when employed to free the space beneath the dial of misplaced loops, threads or other obstructions;

Fig. 4 is a similar detail illustrating the positions of the parts;

Fig. 5 is an explanatory detail enlarged,

showing one of the transfer instruments, the needles, a web holder, and a part of the latch ring;

5 Figs. 6, 7 and 8 are diagram plans illustrating different positions of an instrument hereinafter referred to;

10 Fig. 9 is a diagram plan illustrating the improper detention of a thickening wale yarn by an obstruction at the verge of the dial; and

15 Fig. 10 is a section drawn to an enlarged scale on the line 10—10 of Fig. 6.

20 While the mechanism referred to above as mechanism auxiliary to the devices for forming the thickening wale for making a fabric having a welt may be of any type, in this instance, I have shown mechanism such as illustrated in my Letters Patent No. 1,282,958. The devices include a dial 4 rotatable in unison with the motions of a needle cylinder 260, the web holder bed 295, web holders *w* and needles *n* by gearing *g*', *g*''.

25 In the normal operation of the machine the needles *n* are first worked to make a beginning selvage from a yarn or yarns fed to them from one of the yarn feed fingers *F*, and the transfer implements *T* carried by the dial 4 are subsequently projected over the heads of depressed needles *n* and above 30 the web holders *w* corresponding to the instruments *T* so projected to take bights of a uniting course and retire with them toward the verge of the dial 4.

35 The needles *n'* Fig. 5, depressed for this purpose may recur as frequently as desired among the others, for instance, they may be every second, fourth or sixth needle.

40 The machine now operates to knit the fabric for the welt *W*. In order to secure the entrance of this fabric in a fold within the needles and under the dial, it is generally necessary to provide an instrument adapted to enter the space between the respective verges of the needle cylinder and the 45 instrument dial 4 (or its equivalent transfer instrument carrier). In my said Patent No. 1,282,958, an appropriate instrument for this purpose is shown in Figs. 2, 3 and 21, comprising a presser *P*, pivoted (see Fig. 6) at *p'* and adapted to be swung on its pivot to 50 pass above the web holders and beneath the instrument dial and beneath the latch ring 550, and thus to rest upon the fabric detained at one edge on the instruments *T* and 55 then in course of increase by the operation of the needles. The place of entry of the working end *p* of the instrument *P* is arranged in respect to the needle wave in the working needles so as to pass above depressed needles only. Usually the inward end of the instrument *P* is bent down. Insertion of the instrument *P* is by an automatic connection from a cam on a pattern surface 120, such as thrust bar 460 working 60 a rocker *p* in turn controlling a wire link

p hooked at one end into a hole in the instrument *P* and driven inward by a compression spring *p*' against which the rocker *p* takes.

65 As shown in my Letters Patent No. 70 1,270,064, dated June 18, 1918, the necessary presence of the end *p* of the instrument *P* in the space between the verge of the needle cylinder and the dial enables it to be employed as the detector or actuator of an 75 alarm device or stop motion. The leading face *y* of the portion of the blade *P* which extends within the circle of needles is now made straight and so arranged as to form a very high angle to the line of the advance of 80 the needles, owing to the point at which blade *P* is pivoted when the blade is entered to the position shown in Fig. 8, and in practice a connection 40 serving either as the 85 striker for an alarm bell *B* or to actuate a stop-motion is attached to the pivoted blade *P*, so that when a needle is broken and left in an elevated position, contact with the leading face of the blade serves to throw it outwardly more or less violently and either 90 rings the bell or stops the machine, or both. The connection 40 may be a spring wire carrying a striker 41; the bell *B* is preferably as shown in Figs. 6 and 7 positioned to spring the wire 40 when the end 95 *p* of blade *P* is within the needles.

99 For purposes about to be explained the automatic device 120 controlling the connection 463 may be so arranged as to enter the instrument *P* a part way into the place occupied by it for making the welt *W*, after the welt *W* has been completed and after the instrument *P* has been withdrawn at the completion of the welt. The last operation 105 in making the welt comprises the projection of the instruments *T* to and beyond the position shown in Fig. 5 to enable the transfer of the detained bights held on the instruments *T* to the needles *n'*; the reentry of 110 presser *P* may immediately follow the passage by it of the last loop of the series transferred. By reason of defective needles, defective bits *T*, or defective motions of either of these parts, a loop *x* may be held up and 115 not transferred, as indicated in Fig. 3.

120 Referring now to Fig. 1, the machine is there shown equipped with the means of my application Serial No. 114,096, comprising the auxiliary yarn guide *t'* for the thickening wale yarn *t* and with automatic means 125 comprising a connection *t* to one of the pattern-operated thrust bars 460 for dropping the yarn guide *t'* to operative position to wrap the wane around a group of needles *n* isolated at the right hand side of Fig. 1 130 by being permitted to remain above their fellows.

135 Unless the loop *x* is disposed of in some way the yarn *t* cannot be withdrawn through the guide *t'* by its take-up means to lie

smoothly against the back of the narrow group of needles n^4 . To permit this the yarn t must be drawn off across the diameter of the needle circle in the position of an increasing chord (see the position t^4 Fig. 9) until it defines a diameter, and then must be recovered through the guide t' during its passage through the position of decreasing chords (see t^3) until the needles n^4 are once 10 more opposite the guide t' . But if in any way the space between the dial 4 and the tops of the needles n is obstructed, this motion cannot take place. A yarn loop such as the loop x is such an obstruction; as shown 15 in Fig. 9, such a loop may hold a run t^4 of the yarn t and prevent its sweep through or recovery during any of the positions represented by the line t^3 .

A single run of yarn in the position of 20 the loop x may also constitute such an obstruction. This may and often does occur in the operation of the machine by the trailing end of some yarn hanging down from the yarn clamps 7 of the machine. This end 25 may be either a loose piece of yarn or a misplaced end of one of the yarns carried by the fingers F.

Referring now to Figs. 6 to 8 and Fig. 10, I have provided the instrument P with a 30 surface y which in the position of inward thrust of the instrument P lies at a slight angle to the radius of the needle circle. By reason of the position of the pivot p' this surface is still capable of performing the 35 function of moving the instrument P outward sharply when struck by a misplaced needle, Fig. 6.

I prefer to sharpen the leading face of the blade P for the purpose of parting the loop 40 or ends of yarn, although it should be understood that even when not so sharpened the strain imposed on such ends or loops of yarn may be depended on to break or tear them. If the leading face of blade P 45 were sharpened to a knife edge, the first broken needle that encountered it would tend to dull this edge; I have therefore overcome this difficulty by making the edge square or slightly under-cut as shown at y in Fig. 10, 50 so as to form a sharp edge at the upper surface of the leading edge of blade P. When thus sharpened the contact of a broken needle does not in any way interfere with the cutting edge. The sharpened edge y should 55 not extend inward farther than the point y^2 , Figs. 6 and 8, in order to leave a round smooth surface at the point p^2 to permit it to act as a presser to inwardly dispose the welt fabric W.

60 The operation of the devices will now be understood immediately after the completion of the welt W by the transfer of the last withheld bight from the bits T, presser P is automatically entered to the position 65 shown in Fig. 2 and in Fig. 7, by proper

actuation of the connection 463 by drum 120. If any such loop as the loop x , or a piece of loose yarn, or any other obstruction now occupies the space between the verge of the dial 4 and the heads of the needles, the edge 70 y encounters and severs it. Since this obstruction in the nature of the case can only be a loop of the breakable uniting course, or a waste run or loop of yarn, damage to the fabric is prevented, and the space between 75 the verge of the dial x and the heads of the needles is left open for the subsequent operation of the guide t' to lay the thickening yarn t properly. When the presser P is all the way in, the striker 41 is in contact with 80 the edge of bell B and through the agency of mechanism 463, p^6 , p^4 , which moves presser P, additional strain is placed on the presser to such an extent that the connection 40 is actually sprung when the striker 85 is in contact with the bell, and so that the presser is adapted to offer a stronger resistance to deflection by the held-up yarns or bights by this means, in addition to the effect of the higher angle of its leading 90 edge y .

In order that the strain of severing such a loop shall not interfere with the proper withdrawn position desired for the bits T during knitting for the remainder of the 95 article, a preferred procedure is to permit the means for projecting the bits T to their outward transfer position and for withdrawing them to their idle position to continue in action for several courses after the 100 insertion to space-clearing position of the presser P. This has no effect on the knitting, but insures that the bits T remain in their withdrawn position, whether or not one or more of them have been pulled out 105 by severing loops carried by them.

The presser P may remain in the position of Fig. 7 until the heel or toe knitting is to take place.

I claim:

1. A knitting machine having therein in combination, auxiliary yarn delivery means adapted to coöperate with certain needles only, and yarn parting means adapted to clear misplaced yarns from the path swept 115 by the auxiliary yarn.

2. A knitting machine having therein needles, means for actuating them and means for feeding yarn to them, in combination with means for delivering an auxiliary yarn from a position causing it to float behind the needles, and yarn parting means adapted to clear the space behind the needles of misplaced yarn for the free passage 120 of the auxiliary yarn floats.

3. A knitting machine having therein needles, and means for actuating them, yarn-holding means above and behind the needles, and yarn-delivering means for an auxiliary yarn adapted to deliver its yarn to 130

and float it behind certain of the needles respectively, in combination with means operating above and behind the needles and between the fabric and said yarn-holding means to part misplaced yarns from attachment to the fabric and thereby to clear a path for the floats of auxiliary yarn.

4. An automatic knitting machine having therein in combination, auxiliary yarn-delivery means adapted at certain times to cooperate with certain needles only to make thickened-wale structures, movable yarn-parting means adapted to clear misplaced yarns from the path swept by the auxiliary yarn, and means for moving said parting means to operative position coördinately with the operation of the auxiliary yarn-delivery means.

5. A circular knitting machine having therein needles and means for actuating them, yarn-holding means above and within the needles, and means for delivering an auxiliary yarn in relation to the needles to make thickened-wale structures, in combination with means adapted to be moved into the space between said yarn-holding means and said needles to clear said space of obstructing misplaced yarns for the free passage of the auxiliary yarn.

30 6. A circular knitting machine having therein needles and means for actuating them, means for making inturned welts, means for making thickened-wale structures by the addition of an auxiliary yarn, and means acting after the completion of the welt for clearing a space behind the needles of obstructing yarns to insure free passage of the thickening-wale yarn.

7. A knitting machine of the kind having therein means for withholding within a circle of needles bights of yarn for the uniting course of an inturned welt, and having therein means actuated to feed a thickening wale auxiliary yarn to certain needles only after the welt-forming operation, in combination with means for sweeping the space between the needles and the bight-withholding devices clear of obstructing yarns acting prior to the passage therethrough of a float 50 of the auxiliary yarn, and after the completion of the welt.

8. A knitting machine having therein means for automatically producing fabrics with inturned welts including a presser for entering the inturned fold of the welt during making, said presser having a yarn-severing portion, in combination with means

for positioning the presser after the completion of a welt to bring its severing edge in contact with misplaced runs of yarn.

9. In a knitting machine, the combination of a welt presser having a severing edge, means for forming an inturned welt by means including the presser, and means for positioning the presser after the formation of the welt to cause its severing edge to sweep the region behind the needles of obstructing yarn attached to the fabric.

10. In a knitting machine the combination of the needles and bight-detaining means for forming a welt, with a presser for the welt fabric having a severing edge, a connection adapted to be operated by the presser when struck by a misplaced needle to actuate an alarm or stop device, and yielding means to position the presser after use for welting to bring said edge into the path of misplaced needles and misplaced yarns to be operated by such needles and to sever the yarns, respectively.

11. A knitting machine having therein, in combination means for delivering an auxiliary yarn at predetermined times in the production of the fabric, a device for parting above and behind the fabric a misplaced or obstructing yarn attached to the fabric and likely to prevent the proper operation of the auxiliary yarn-delivering means, and means for positioning the parting means coördinately with the operation of the said delivering means.

12. A presser, yarn-severing and detector device for use in knitting machines comprising a pivoted instrument having a free end adapted to ride on and inwardly press a fold of the fabric, said structure having an edge lying crosswise of the direction of motion of the needles and fabric near the needles sharpened at its juncture with one face of the structure, and thereby adapted both to sever misplaced yarn and to withstand the blows of misplaced needles without substantial damage to the severing edge, in combination with yielding means for forcing said instrument inwardly during welting and for positioning the part of said instrument bearing said edge in line with the needles during subsequent knitting, and a connection for operation by the instrument when it is struck by a misplaced needle.

Signed by me at New York, N. Y., this 18th day of May, 1920.

ROBERT W. SCOTT.
